US00D886382S

(12) **United States Design Patent** (10) Patent No.: **US D886,382 S**
(45) Date of Patent: ** Jun. 2, 2020

(54) **RAZOR HANDLE**

(71) Applicant: **PCMR International Ltd.**, Beit She'an (IL)

(72) Inventors: **Michael Dubin**, Marina Del Rey, CA (US); **Javier Hall**, Marina Del Rey, CA (US); **Shlomo Zucker**, Marina Del Rey, CA (US)

(73) Assignee: **PCMR INTERNATIONAL LTD.**, Beit She'an (IL)

(**) Term: **15 Years**

(21) Appl. No.: **29/661,156**

(22) Filed: **Aug. 24, 2018**

Related U.S. Application Data

(63) Continuation-in-part of application No. 29/655,193, filed on Jun. 29, 2018, now Pat. No. Des. 870,382, which is a continuation of application No. 29/639,847, filed on Mar. 9, 2018.

(57) **CLAIM**

We claim the ornamental design for a razor handle, as shown and described.

DESCRIPTION

FIG. 1 is a front perspective of a razor handle according to an embodiment of our new design;

FIG. 2 is a left elevational view of a razor handle according to an embodiment of our new design;

FIG. 3 is a right elevational view of a razor handle according to an embodiment of our new design;

FIG. 4 is a top plan view of a razor handle according to an embodiment of our new design;

FIG. 5 is a bottom plan view of a razor handle according to an embodiment of our new design;

FIG. 6 is a front elevational view of a razor handle according to an embodiment of our new design; and,

FIG. 7 is a rear elevational view of a razor handle according to an embodiment of our new design.

The broken lines illustrate a button, handle end, and docking features and form no part the claimed design.

1 Claim, 7 Drawing Sheets
